CLAIM

The ornamental design for a crucifix, as shown and described.

DESCRIPTION

FIG. 1 is a front elevational view of a crucifix showing our new design.

FIG. 2 is a right side elevational view.

FIG. 3 is a left side elevational view.

FIG. 4 is a rear elevational view.

FIG. 5 is a top plan view.

FIG. 6 is a bottom plan view.

Liquid is contained in the crucifix and displayed in FIGS. 1 and 4.
